UNITED STATES PATENT OFFICE.

WILLIAM E. KEACH, OF FITCHBURG, MASSACHUSETTS.

DESIGN FOR A CLEARER FOR DRAWING-ROLLS.

SPECIFICATION forming part of Design No. 32,339, dated March 13, 1900.

Application filed February 12, 1900. Serial No. 5,019. Term of patent 14 years.

To all whom it may concern:

Be it known that I, WILLIAM E. KEACH, a citizen of the United States, residing at Fitchburg, in the county of Worcester and State of

5 Massachusetts, have invented and produced a new and original Design for Clearers for Drawing-Rolls, of which the following is a specification, reference being had to the accompanying drawing, forming a part thereof,

10 where the figure is a view in perspective of a clearer, showing my new design.

As shown in the drawing, the leading and material feature of my design consists of the series of flat rectangular sections A and 15 curved sections B, the curved section being separated from the rectangular section by the

groove C and the rectangular and curved sections being separated from each other by the spaces D, the central one of which is wider than the other two. 20

Having described my invention, what I claim as new, and desire to secure by Letters Patent, is—

The design for a clearer for drawing-rolls, as herein shown and described. 25

In testimony whereof I have signed my name to this specification in the presence of two subscribing witnesses.

WILLIAM E. KEACH.

Witnesses:

ALVAH M. LEVY,
CLARENCE E. TUPPER.
